UNITED STATES PATENT OFFICE.

CHARLES C. PENFOLD, OF BUFFALO, NEW YORK.

DESIGN FOR A MEDAL.

SPECIFICATION forming part of Design No. 17,017, dated December 7, 1886.

Application filed October 11, 1886. Serial No. 215,957. Term of patent 3½ years.

To all whom it may concern:

Be it known that I, CHARLES C. PENFOLD, a citizen of the United States, residing at Buffalo, in the county of Erie and State of New York, have invented and produced a new and original Design for Decorations or Medals, of which the following is a specification, reference being had to the accompanying drawing, forming a part thereof.

10 The figure represents an elevation of a parade badge or decoration.

The leading features of my design are, first, a bar. Dependent from this is the decoration proper, consisting of four shields arranged in the form of a cross—viz., one at the top, one at the bottom, and one each side. Over the points of the shields is a circular device having an outer rim. In the center is an anchor, and on this a shield bearing thereon a trans-

verse bar on which are letters. In the spaces 20 between each shield is a sheathed sword, and under them, in a circle, a wreath of leaves. The shields have raised edges. On the lower or bottom shield is an open book (Bible) and a skeleton hand thereon. 25

I claim—

The design for a medal, badge, or decoration herein shown and described, the same consisting, essentially, of the four shields arranged as described, and a central circular 30 device having thereon an anchor, and a shield on the anchor, the spaces between the four shields occupied by swords and a wreath.

CHARLES C. PENFOLD.
